UNITED STATES PATENT OFFICE.

DAVID E. HUNTER, OF CAMBRIDGE, MASSACHUSETTS, ASSIGNOR TO LIBRARY BUREAU, OF BOSTON, MASSACHUSETTS, A CORPORATION OF NEW JERSEY.

PANEL CONSTRUCTION.

969,163.

Specification of Letters Patent. Patented Sept. 6, 1910.

Application filed October 20, 1909. Serial No. 523,571.

To all whom it may concern:

Be it known that I, DAVID E. HUNTER, a citizen of the United States, and resident of Cambridge, in the county of Middlesex 5 and State of Massachusetts, have invented new and useful Improvements in Panel Construction, of which the following is a specification.

This invention relates to a panel construction particularly designed for use in cabinets and cases such as museum cabinets and its principal objects are to provide a novel and improved frame joint and a panel construction in which the panel frame and the 15 panel piece shall be free from the possibility of relative movement and consequent distortion of the panel by sagging.

While the invention is applicable to the construction of panels generally, it will, I 20 believe, find its most useful application in panels used as doors for cabinets or the like wherein there is the greatest tendency to sagging and distortion owing to the fact that the whole weight of the structure is 25 borne by one edge. I will therefore address my description to the embodiment of the invention in a door; it will be understood however that the invention is capable of more general use and such general use is 30 contemplated by the claims.

In the accompanying drawings which illustrate one embodiment of the invention,—Figure 1 is a front elevation of the upper corners of a door illustrating the invention, 35 the other parts being broken away; Fig. 2 is a vertical section on line 2—2 of Fig. 1; Fig. 3 is a rear elevation of one upper corner of the door or panel construction shown in Fig. 1; Fig. 4 is a perspective view of the 40 top frame member viewed from the rear; Fig. 5 is a perspective view of one of the upright or side frame members viewed from the rear; Fig. 6 is a cross section on line 45 6—6 of Fig. 1; Fig. 7 is a front elevation of the lower corners of the door or panel construction, the other parts being broken away; Fig. 8 is a vertical section on line 8—8 of Fig. 7; and Fig. 9 is a plan view of one end of the bottom frame member.

50 Referring to the drawings, A represents the panel piece which as herein shown is made of glass. Engaging the edges of the panel piece A at all four sides is a channeled panel frame the top member of which B, 55 and the side or vertical members of which

B', preferably have an identical cross-sectional form, shown in Fig. 2. The channel of these frame members, formed by the channel walls b, b' and the transverse web b² at the bottom of the channel, engages the 60 edge of the panel A as presently to be described. The wall b extends beyond the transverse web b² as shown at b³, the wall b, b³ forming the face of the panel frame.

When the panel piece and frame members 65 are assembled and supported at one vertical edge, as when used in a door, it will be obvious that the strain between the top and side frame members will subject the top part of the frame to tension in a direction longitudinal of the top frame member B. I therefore provide a dove-tail joint between the top and side frame members consisting of the tenon b⁴ formed from the wall b, b³, and undercut or notched as shown at b⁵ to provide an enlarged head. The channel wall b' of the top member B is also provided with the notch b⁶ forming the half dovetail b⁷ which registers with the lower end of dove-tail b⁴. The adjacent vertical member B' 70 is provided with a mortise b⁸ undercut as shown at b⁹ to fit the tenon b⁴. This mortise is cut from the face wall b of the channel. The cross web b² of the frame member B' 75 and also the channel wall b' are cut away 80 as best shown in Fig. 5, the latter made with a mortise b¹⁰ to fit the half tenon b⁷; and the cross webs b² of the frames meet at their ends, so that when the two frame members are assembled the channel walls and cross 85 webs will fit edge to edge thus forming a closed channel for the panel piece A. When the panel A is inserted within this channel 90 it will lock the mortise and tenon in place and prevent their dislodgment by relative 95 forward or backward movement.

As the strain at the bottom of a door frame, when hung at the side edge, subjects the bottom part of the frame to compression rather than tension, it is not necessary to 100 use a form of joint particularly adapted to withstand tension. While any form of joint may be used at this point I recommend the following: The bottom frame member B³ instead of having a cross-sectional form like the other frame members, may be H-shaped in cross section as shown in Fig. 8. This is for the reason that the bottom frame member when the structure is used as a door 105 usually comes in contact with the floor of 110

the cabinet or case, whereas the top and vertical frame members make contact with similar panel frames at the sides and top of the case, as illustrated in Fig. 6, wherein E 5 and E' represent respectively an adjacent and similar panel frame and panel. The joint between the bottom frame member B³ and the side frame members B' may therefore consist of a slot through the transverse 10 web b² of the side members through which extends the tongue b¹¹ cut from the transverse web b² of the bottom channel member B³ by cutting away the vertical webs b¹² of said H-shaped member. The tongue b¹¹ 15 after being passed through the slot in the web b² of the side member may be headed over as shown at b¹³ in Fig. 7.

Hinges or butts C may be secured in any suitable manner to the panel frame and are 20 preferably secured in such manner as to cover the joint at the top of the door as shown in Fig. 1 thus affording additional security against dislodgment of the joint making parts. If desired, a plate similar 25 to the plate of the hinge or butt C may also be fastened over the joint at the outer or right hand corner of the door as viewed in Fig. 1, but I believe that ordinarily such plate will not be found necessary, since the 30 panel A itself will adequately lock the joint in place.

It is found in practice that no matter how well made and how rigid may be the frame of such panel or door, there is a tendency for 35 the same to sag by reason of a yielding of the corner joints and a slipping between the frame members and panel. It is impossible to procure commercial glass panels cut sufficiently accurately to fit evenly against 40 the bottom webs b² of the channel frames; and even if a glass panel could be procured cut with sufficient accuracy to abut at its edges against the webs b² and so to hold the frame against sagging, any minute inaccuracy 45 would still bring undue weight to bear at certain points with liability to break or crack the glass. In order to distribute the strain evenly on the glass and to prevent the possibility of cracking or breaking the same 50 and to prevent the panel construction from slipping and sagging, I leave a clearance between the edges of the panel and the webs b², and insert between the surfaces of the panel and the walls of the channel an adhesive 55 packing material, such as tarred paper, which makes frictional contact with the surfaces of the glass panel A, thus preventing relative slipping between the panel and the panel frame, and distributing the 60 strain due to the weight of the structure evenly throughout the panel A instead of concentrating it at one point or a few points. This adhesive packing is shown in Fig. 2 at d. It may be compressively held in contact 65 with the surface of the panel A simply

by forcing it into the channel, or it is preferably held in such compressive contact by the use of a strip of spring metal d' like that shown in my co-pending application Serial No. 475,548.

When the parts are assembled as described, and the panel used as a door and supported at the side edge by means of the hinges C, it will be seen that the strain due to the weight of the door will be so distributed that the left hand frame member B' (as viewed in the drawings) will serve as an abutment for the panel, the weight of which tends to thrust the lower end of the panel toward the left, and the top frame member B will support the tension or strain toward the right due to the weight of the door, the adhesive packing between the panel and the top frame member holding the panel by frictional engagement from 85 movement longitudinally of the top frame member.

I claim:

1. In combination, a panel piece, a channeled frame engaging the edges of the panel piece, an adhesive packing within the channel of the frame in contact with one surface of the panel piece, and a spring between the wall of the channel and the adhesive packing adapted to press the latter into close 95 frictional engagement with said panel piece.

2. In combination, a panel piece, a channeled frame engaging the edges of the panel piece, an adhesive packing on each side of the panel piece within the channel of the frame in contact with both surfaces of the panel piece, and a spring between the wall of the channel and one of the adhesive packings adapted to press said packings into close frictional engagement with said panel 105 piece.

3. In a panel construction, a panel piece, and a pair of channel metal frame members, each comprising a pair of webs or walls overlying and embracing the panel piece at 110 its border and lying substantially parallel thereto, and connected by a transverse web extending across the edge of the panel piece, one at least of said webs overlying the border of the panel piece being formed into a 115 dovetail tenon at its end and the adjacent web of the other frame member having therein near its end a mortise engaging said tenon, the mortise and tenon corner-joint thereby formed adapted to be separated 120 when the panel piece is removed by moving said frame members relatively in a direction perpendicular to the plane of the frame formed by said members, and said panel piece adapted to hold said mortise and tenon 125 in interlocked relation when the parts are assembled.

4. In a panel construction, a pair of channeled frame members each having a face wall forming one of the legs of the channel 130

- and extending in the opposite direction beyond the web forming the bottom of the channel, the face walls of one of said frame members formed into a dovetail tenon and 5 the face wall of the other of said frame members provided with a corresponding dovetail mortise, said mortise and tenon forming a corner joint between said members.
- 10 5. In a panel construction, a pair of channeled frame members each having a face wall forming one of the legs of the channel and extending in the opposite direction beyond the web forming the bottom of the 15 channel, the face walls of one of said frame members formed into a dovetail tenon, part of which lies on one side and part on the other side of the web forming the bottom of the channel, and the face wall of the other 20 of said frame members provided with a corresponding dovetail mortise, said mortise and tenon forming a corner joint between said members.
6. In a panel construction, a pair of channeled frame members each having a face wall forming one of the legs of the channel and extending in the opposite direction beyond the web forming the bottom of the channel, the face wall of one of said frame 25 members formed into a dovetail tenon, and the face wall of the other of said frame members provided with a corresponding dovetail mortise, said mortise and tenon forming a corner joint between said members, and a panel, whose edges are engaged by said channeled frame members, adapted to hold said tenon and mortise in interlocked relation when the parts are assembled.
- 30 7. A panel construction comprising a panel piece, a separable rectangular channeled panel frame whose channels engage the edges of said panel piece, the upper corners of said frame provided with dovetail mortise and tenon joints adapted to be held in interlocked relation by the panel piece, and an adhesive packing compressively held between the walls of the channels and the surface of the panel piece, 35 adapted to prevent relative movement or slipping between the frame and panel piece.
- 50 8. In a panel construction, a panel piece and a pair of channeled frame members en-
- gaging the edges of said panel piece, both walls of the channels of said frame members 55 being provided respectively with interlocking tenons and mortises, forming a corner joint, and the panel piece adapted to hold said tenons and mortises in interlocked relation when the parts are assembled. 60
9. In a panel construction, a pair of channeled frame members, one a top member and the other a side member, each having a face wall forming one of the legs of the channel and extending in the opposite direction beyond the web forming the bottom of the channel, the face wall of one of said frame members formed into a dovetail tenon, part of which is on one side and part on the other side of said web forming the 70 bottom of the channel, and the face wall of the other of said frame members provided with a corresponding mortise, and the opposite wall of the channel of the first named member formed into a half dovetail tenon 75 registering with the corresponding part of the tenon formed from the face wall, and the opposite wall of the channel of the second named member provided with a mortise adapted to engage said half tenon, and a 80 panel whose edges are engaged by said channeled frame members.
10. In a door, an upright channeled frame member, a top channeled frame member, means secured to the upright frame 85 member to support the door at one edge, the two frame members rigidly secured together to withstand tension longitudinal of the top frame due to the weight of the door, a panel whose edges are within said 90 channeled frame members, and an adhesive packing compressively held between the walls of the channel of the top frame member and the surface of the panel and holding said panel in said channel by close frictional 95 engagement with said surface, said upright frame member serving as an abutment for said panel, and said top frame member supporting the tension due to the weight of said door. 100

Signed by me at Boston, Massachusetts this eighth day of October 1909.

DAVID E. HUNTER.
